(57) **CLAIM**

The ornamental design for a holder for intraocular lens, as shown and described.

DESCRIPTION

FIG. 1 is a front view of a holder for intraocular lens showing our new design;

FIG. 2 is a right side view thereof;

FIG. 3 is a top plan view thereof;

FIG. 4 is a bottom view thereof;

FIG. 5 is a perspective view thereof;

FIG. 6 is a sectional view thereof taken on line 6-6 of FIG. 1;

FIG. 7 is a sectional view thereof taken on line 7-7 of FIG. 2; and,

FIG. 8 is a reference perspective view thereof showing a condition in use.

A rear view and a left side view are omitted because the rear view is identical to the front view and the left side view is identical to the right side view.

The broken lines in FIG. 8 are included for the purpose of illustrating a portion of the holder for intraocular lens that forms no part of the claimed design.
